UNITED STATES PATENT OFFICE.

JOSEPH FISCHER, OF FAITH, SOUTH DAKOTA.

AERIAL PROPELLER.

Application filed August 28, 1925. Serial No. 53,155.

This invention relates to aerial propellers and has as its object to provide a propeller which will be more efficient in its action than aerial propellers as ordinarily constructed.

One of the more specific objects of the invention is to provide a propeller having its blades so constructed as to minimize slip, the blades being so formed that air will be compressed behind each blade of the propeller as the propeller rotates and thus enable the propeller to exert greater tractive force than is obtainable in the operation of propellers where the percent of slip is relatively great.

Another object of the invention is to provide an aerial propeller of such construction that cavitation will be minimized in the openings thereof, and air will be pocketed and banked behind the blades of the propeller so that the blades will, in effect, operate against a more or less compressed bank of air rather than against rarefied air.

Another object of the invention is to so construct the blades of the propeller that the portions thereof which constitute the means for banking air behind the blades will tend likewise to prevent distortion of the blades by continually reinforcing the blades.

In the accompanying drawings:

Figure 1 is a perspective view of a propeller embodying the invention.

Figure 2 is a front elevation of the propeller.

Figure 3 is an end view of the propeller.

Figure 4 is a side elevation of the propeller.

Figure 5 is a vertical sectional view taken substantially on the line 5—5 of Figure 2, looking in the direction indicated by the arrows.

Figure 6 is a horizontal sectional view taken substantially on the line 6—6 of Figure 2, looking in the direction indicated by the arrows.

Figure 7 is a similar view taken substantially on the line 7—7 of Figure 2, looking in the direction indicated by the arrows.

In the illustrated embodiment of the invention, the propeller comprises a pair of counterpart blades indicated in general by the numeral 1, and a hub portion 2 to which the standard hub (not shown) may be fitted and the propeller thus mounted upon the propeller shaft of the air craft to be propelled. Each of the blades 1 comprises a

body 3 which is of approximately ovate marginal contour and is substantially flat at its forward face, which is indicated by the numeral 4, and has its rear face slightly convex, as indicated by the numeral 5, the body being relatively thin, as will be observed by reference to Figures 5, 6 and 7 of the drawings. The leading edge of the blade is indicated by the numeral 6 and the trailing or opposite edge portion is indicated by the numeral 7. At its last mentioned edge portion, the blade is formed to provide an air-compacting pocket indicated by the numeral 8. This pocket extends from the tip or outer end of the blade longitudinally of the trailing edge portion of the blade to the hub portion 2 and merges with the latter portion.

By reference to the several figures of the drawings, it will be observed that the pockets 8 are located at the forward faces 4 of the blades and that the walls of these pockets are rounded transversely, the outer wall 9 of each pocket being spaced from and opposing the said flat face 4 of the respective blade. Said wall 9 of the pocket is merged at its inner end with the surface of the hub portion 2, as indicated by the numeral 10, and the edge of the said wall is curved longitudinally near the outer end of the pocket, as indicated by the numeral 11, so that each pocket is of gradually decreasing depth from a point inwardly of the tip of the respective blade to the outer end of the pocket.

It will furthermore be observed by reference to the drawings, and particularly Figure 2, thereof, that the material of the blades is gradually thickened along the bottoms of the pockets, in the direction of the hub portion 2, as indicated by the numeral 12, so that the pockets are of gradually decreasing depth in the direction of their inner ends. As the pockets are located at the trailing edge portions of the blades, their open sides are presented in the direction of rotation of the propeller and it will, therefore, be evident that as the propeller is rotated, air will be trapped in the pockets and compacted so as to establish, in effect, a bank of air against which the body 3 of the respective blades may act. Therefore, cavitation is reduced to a minimum and the air surrounding the revolving propeller is not so rarefied as where cavitation is caused to a marked degree. Furthermore, there is less slip in the operation of the propeller embodying the in-

vention than would be the case if the pockets were not present. By gradually decreasing the height of the walls 9 of the pockets near their outer ends, and forming the pockets 5 of maximum depth at their intermediate portions, the greatest efficiency is obtained in compacting the air and, at the same time, the air trapped in the pockets may escape with minimum resistance, by way of the 10 outer ends of the pockets, through centrifugal force, in the rotation of the propeller.

It will be observed that the blades are oppositely diagonally disposed, as is the case in the ordinary propeller, and that the 15 pockets of the two blades are substantially co-extensive as regards their outer walls 9. It will be understood, of course, that while the propeller, in the illustrated embodiment, embraces two blades, a greater number of 20 blades may be provided.

Having thus described the invention, what I claim is:

1. An aerial propeller comprising oppositely extending blades and an intermediate 25 hub portion, each blade having an air-compacting pocket extending the full length of the trailing edge portion thereof and including a wall confronting the forward face of the blade, the said wall, from a point near

the outer end of the pocket being gradually decreased in depth in the direction of the said end of the pocket.

2. An aerial propeller comprising radially extending blades and an intermediate hub portion, each blade comprising a substantially flat body of ovate marginal contour disposed obliquely to the axis of the hub portion, and an air-compacting pocket extending along the trailing edge portion of the blade body.

3. An aerial propeller comprising oppositely extending blades and an intermediate hub portion, each blade comprising a substantially flat body disposed obliquely to the axis of the hub portion, and an air-compacting pocket extending along the trailing edge portion of the blade body, said pocket being transversely concave in cross section and having a wall confronting the forward surface of the blade body, said wall merging at its inner end into the hub portion and the material of the blade being gradually thickened toward the hub portion whereby the pocket gradually decreases in depth toward its inner end.

In testimony whereof I affix my signature.

JOSEPH FISCHER. [L. S.]
